DESIGN FOR A CLAMP

Delbert C. Blackmon, Olean, N. Y.

Application August 9, 1948, Serial No. 147,998

Term of patent 14 years

(Cl. D17—6)

To all whom it may concern:

Be it known that I, Delbert C. Blackmon, a citizen of the United States, residing in the city of Olean, county of Cattaraugus, and State of New York, have invented a new, original, and ornamental Design for a Clamp, of which the following is a specification, reference being had to the accompanying drawing, forming part thereof.

In this drawing:

Fig. 1 is a side view of a clamp showing my new design.

Fig. 2 is an edge elevational view of the same.

Fig. 3 is a front end view.

Fig. 4 is a rear end view of the same.

I claim:

The ornamental design for a clamp, as shown.
